UNITED STATES PATENT OFFICE

92,373

DESIGN FOR A POCKET LIGHTER

Henry T. Schiff, Chicago, Ill.

Application September 2, 1933, Serial No. 49,195

Term of patent 7 years

To all whom it may concern:

Be it known that I, HENRY T. SCHIFF, a citizen of the United States, residing at Chicago, in the county of Cook and State of Illinois, have invented a new, original, and ornamental Design for Pocket Lighters, of which the following is a specification, reference being had to the accompanying drawing, forming part thereof.

The drawing shows a perspective view of my new and improved pocket lighter.

I claim:

The ornamental design for a pocket lighter, as shown.

In testimony whereof I have hereunto affixed my signature.

HENRY T. SCHIFF.
